UNITED STATES PATENT OFFICE.

WILLIAM SUMNER, OF LIVERPOOL, ENGLAND, ASSIGNOR TO UNIVERSAL ENGINEERING COMPANY, LIMITED, OF LIVERPOOL, ENGLAND.

ADVERTISING APPARATUS.

1,224,232.

Specification of Letters Patent.

Patented May 1, 1917.

Application filed January 5, 1915. Serial No. 687.

To all whom it may concern:

Be it known that I, WILLIAM SUMNER, a subject of the King of Great Britain, and a resident of Liverpool, England, have invented certain new and useful Improvements in and Relating to Advertising Apparatus, of which the following is a specification.

This invention relates to improvements in advertising apparatus, whereby a series of panels, tablets, or the like devices may be successively displayed, without the aid of lifting or traveling chains as previously proposed. The invention is particularly applicable for use in displaying *scrutine* a series of small advertising panels the control mechanism for which is adapted to be actuated by the operation of, say, a cash register, cash till, or the like, the opening of a door, or treadling on a door mat.

According to this invention, a series of advertisement display panels is provided and nested together in a single bank, a reciprocatory lifter or mover element being fitted and adapted to be traversed by any suitable articulation across the end one of the bank of panels, a lip or the like on the reciprocatory element being adapted to engage and lift or move the end panel above or clear of the bank, such displaced end panel being then pressed by a light spring or analogous element toward the other end of the bank, when on the next stroke of the reciprocatory element a pin or projection on the element engages the displaced panel and inserts it at the front of the bank, each complete reciprocation of the element thus causing an end panel to be moved from one end of the bank of panels and deposited at the other end.

The invention is illustrated in the accompanying drawings, in which Figure 1, is a front elevation, partly in section, of an advertisement display device. Fig. 2, is an end view, in section on the line A—A Fig. 1. Fig. 3, is a fragmentary end section, analogous to Fig. 2, but showing the displaced advertisement panel being reinserted at the front of the bank of panels.

The advertisement panels 1 are nested together in a series or bank within the casing 2 of the apparatus, and in the form of the apparatus shown the panels rest on brackets 3 at each side of the machine. Mounted so that it may be reciprocated across the rear one of the bank of panels 1 is an element or elements 4, preferably one at

each side of the machine, as indicated. These elements may be reciprocated in any suitable manner. In the example shown, they are pivotally hung from lugs 5 upon a rod 6, the ends of the rod being vertically guided within slots 7 in the casing, and raised or lowered by means of a rocking lever comprising arms 8, pivoted at 9, and connected by a crossbar 10, the cross-bar being provided with an arm 11 adapted to be connected to some moving part, say, of a cash register, a door connection, or the like, by the operation of which the lever 11, 8, may be rocked and the elements 4 reciprocated. The arms 8 are slotted at 12 to provide for the play of the rod 6 as it slides in the slot 7. The reciprocatory elements 4 are also provided with projections or pins 13 to engage the upper edges of the panels. Mounted at the rear of the bank of panels 1 is a spring or springs, 16 the upper end of which is adapted to press forward the rearmost panel when it has been lifted by the element 4 clear of the bank. The upper part of the casing may be fitted with a fixed advertisement panel 19, and down each side at the front of the casing are fitted guides 20, set in to form obliquely shaped faces at 21, just above the display aperture 22 of the casing. This display aperture may be inclosed by a glazed panel 22.

The operation of the device is as follows:—As the arm 11 of the rocking lever is moved down by its articulation, say by the operation of opening the drawer of a cash register, or the like, the arms 8 lift the elements 4, the lips 14 on which raise the rearmost panel of the bank of panels 1 until, when the lowest edge of this rearmost panel clears the top of the bank as illustrated in dotted lines Fig. 2, the light spring 16, which has been rearwardly deflected by this operation to the dotted position shown, pushes the displaced panel flat against the vertical side guides 20. The lip 14 engaging behind the then rearmost panel holds the element 4 back while the panel is pushed forward. The underside of the lip 14 is beveled as shown to enable it to clear the upper edge of the rearmost panel on the down stroke. On the return or up stroke of the arms 8 the pins 13 engaging the upper edge of the displaced panel, force it downward, the spring 16 maintaining it parallel during this operation against the

front guides 20 until its lower edge is caught by the inclined faces 21 and deflected inward against the front panel of the bank, pressing all the panels back as shown in Fig. 3, until it is finally positioned at the front of the bank and opposite the display aperture 22 of the casing. During this positioning operation, the elements 4 have been riding down in contact with the rearmost panel, and the lips 14 now engage below the rearmost panel of the bank, which is lifted on the next upward stroke, pushed forward by the spring 16, and positioned at the front of the bank by the downward push of the pins 15, as previously described. As the lever 11, 8, is operated, therefore, each panel of the bank is taken *seriatim* from the rear and displayed at the front. Stops 8^a, 8^b may be fitted to limit the oscillation movement of the arms 8, and instead of the element 4 being moved by a rocking lever, as shown, the rod 6 may be lifted direct in any suitable manner.

The panels may be made of aluminium, cardboard or cardboard protected with a metal edging, celluloid, or any suitable material. The advantage of such an arrangement of display advertising lies in the fact that any advertisement of the series may be readily removed or replaced as its period expires.

I claim:

1. In an advertising apparatus, in combination; a bank of panels; a rocking lever adapted to move the panel at one end clear of the bank; a spring for moving the displaced panel across the bank, and a projection on the rocking lever for positioning the panel at the other end of the bank.
2. In an advertising apparatus, in combination; a bank of panels; a rocking lever; an element pivotally hung from the rocking lever and adapted to move the panel at one end clear of the bank; a spring for moving the displaced panel across the bank; and a projection on the rocking lever for positioning the panel at the other end of the bank.
3. In an advertising apparatus, in combination; a bank of panels; a rocking lever; an element pivotally hung from the rocking lever and adapted to move the panel at one

end clear of the bank; a spring for moving the displaced panel across the bank; a projection on the rocking lever for positioning the panel at the other end of the bank; and means for guiding the panel into its new position.

4. In an advertising apparatus, in combination; a bank of panels; a rocking lever; an element pivotally hung from the rocking lever and adapted to move the panel at one end clear of the bank; a lip on the pivotal element for engaging the panel; a spring for moving the displaced panel across the bank; a projection on the rocking lever for positioning the panel at the other end of the bank; and means for guiding the panel into its new position.

5. In an advertising apparatus, in combination; a bank of panels; a rocking lever; an element pivotally hung from the rocking lever adapted to move the panel at one end clear of the bank; a lip on the pivotal element for engaging the panel; a spring on the pivotal element for insuring engagement of its lip with the end panel; a spring for moving the displaced panel across the bank; a projection on the rocking lever for positioning the panel at the other end of the bank; and means for guiding the panel into its new position.

6. In an advertising apparatus, in combination, a bank of panels, a pivoted reciprocating member having a lip adjacent one end thereof, said lip adapted to engage under the rearmost panel and move the same clear of the bank of panels, means on one end of the reciprocating member for engaging the adjacent panel, an operating lever for moving said pivoted reciprocating member, means for limiting the movement of said operating lever for preventing the reciprocating member from passing over the panels, and resilient means for holding the reciprocating member into engagement with the bank of panels.

In testimony whereof I affix my signature in presence of two witnesses.

WILLIAM SUMNER.
